(74) Attorney, Agent, or Firm — Crestron Electronics, Inc.

(57) **CLAIM**

The ornamental design for an audio pod, as shown and described.

DESCRIPTION

FIG. 1 shows a top perspective view of an audio pod, showing our new design;

FIG. 2 shows a bottom perspective view thereof;

FIG. 3 shows a front elevation view thereof;

FIG. 4 shows a rear elevation view thereof;

FIG. 5 shows a left side elevation view thereof;

FIG. 6 shows a right side elevation view thereof;

FIG. 7 shows a top plan view thereof; and,

FIG. 8 shows a bottom plan view thereof.

The broken lines in the figures illustrate the portions of the audio pod that form no part of the claimed design.
